UNITED STATES PATENT OFFICE.

WILLIAM LLOYD, JOHN LLOYD, AND SAMUEL T. NICHOLSON, OF
WILKES-BARRE, PENNSYLVANIA.

STEAM-ELIMINATOR.

No. 839,777.

Specification of Letters Patent.

Patented Dec. 25, 1906.

Application filed May 7, 1906. Serial No. 315,684.

To all whom it may concern:

Be it known that we, WILLIAM LLOYD, JOHN LLOYD, and SAMUEL T. NICHOLSON, citizens of the United States of America, residing at Wilkes-Barre, in the county of Luzerne, in the State of Pennsylvania, have invented certain new and useful Improvements in Steam-Eliminators, of which the following is a specification.

Our invention relates to improvements in steam eliminators or separators for the purpose of eliminating water, entrained moisture, grease, oil, or other impurities from steam and automatically discharging such eliminated water, &c., without waste or loss of steam.

Our present invention is primarily in the nature of an improvement upon the steam-eliminators set forth in Patents No. 600,921, dated March 22, 1898, and No. 677,458, dated July 2, 1901.

The main object of this invention is to so improve the construction and mode of operation of the apparatus as to make its action in opening and closing more certain.

Other features of improvement will be disclosed in the following description.

In the accompanying drawings, Figure 1 is a vertical section of my improved construction of steam-eliminator. Fig. 1^a is a cross-section of the main valve into the collecting-chamber, showing a by-pass valve. Fig. 2 is a sectional plan on the line 2 2, Fig. 1, but drawn to a reduced scale. Fig. 3 is a side elevation of the trip apparatus, drawn to a larger scale than Fig. 1 and with some of the parts in different positions from those of Fig. 1. Fig. 4 is a view of this trip apparatus from the reverse side in a section taken on the line 4 4, Fig. 5. Fig. 5 is a plan view of the trip apparatus, and Fig. 6 is a vertical section of a modification.

In Figs. 1 and 2, A is the baffle-chamber with steam-inlet B and steam-outlet C. Below is the collecting-chamber D with an intermediate valve E. In Patent No. 677,458 a gate-valve was described; but instead of the gate-valve we use a seated valve carried by a vertical spindle e, threaded at e' and passing through a stuffing-box f in the top of the casing and provided on the outside with a hand-wheel f', by turning which the valve E may be raised off or set down onto its seat F. This valve-seat is attached to or forms part

of a flange F', which is clamped between the flanges of the baffle-chamber and the collecting-chamber.

The construction of the baffles will be clearly seen from Fig. 2. The baffles include two corrugated plates 10, cast with or attached to the side walls of the baffle-chamber and set radially therein, and two transverse plates 11 11, with corrugated faces, these transverse plates being also attached to or cast with the body of the baffle-chamber and standing across the middle of the steam-passage through the casing. These corrugated baffle-plates 11 11 are provided with inner ribs 12, arranged radially of the vertical axis of the baffle-chamber.

We prefer to provide the collecting-chamber with a steam-actuated outlet-valve G, covered by a suitable perforated screen 13. This water-discharge valve G is carried on and opened by the stem 14 of the piston 15, which works in the short cylinder 16. This cylinder on one side of the piston is open through the passage 17 to the water-outlet 18. On the other side of the piston there is a connection through a passage 19 (indicated by dotted lines in Fig. 1) to a valve 20 in the steam-space of the collecting-chamber, and this valve is controlled by the float-and-trip mechanism to be described. A spring 60 insures the closing of the valve G to its seat. In Patent No. 677,458 a slide-valve is shown to control a steam-passage, such as 19; but we have substituted for the slide-valve a seat-valve 20, as shown more clearly in Figs. 3 and 4. The valve 20 is carried by a lever 22, pivoted at 23 to the frame H, which is bolted or otherwise secured to some suitable part of the casing of the collecting-chamber. The valve is normally pressed to its seat by a spiral spring 24, acting on a collar 25 on the lower end of a spindle 26, which is pivoted at its upper end to the lever 22. The spring 24 bears at its upper end against the under side of the frame H, Fig. 4.

To open the valve against the action of this spiral spring 24, we provide a cross-shaft 27, mounted in bearings in the frame H and carrying at one end a weighted lever 28 and at the other end a crank 29, with crank-pin 30 engaging the forked lower end of the upright spindle 26.

On the outside of the fixed sleeve, through which the shaft 27 passes, Fig. 5, is pivoted

the lever 31, which carries at its lower end the float 32. This float-lever has a pin-and-slot connection with the weighted lever 28, as by a pin 33 on the float-lever working in a slot 34 in the forward extension 35 of the weighted lever.

Pivoted to a suitable part of the frame H is a weighted catch-lever 36, the purpose of which is to engage with the shoulder 37 on 10 the weighted lever 28 when the descent of the float has tilted this lever 28 to the position shown in Figs. 1 and 3. The long arm of this catch-lever 36 is in such a position as to be acted on by a projecting piece, such as an 15 antifriction-roller 38, on the float-lever when the float rises on a rise of water in the collecting-chamber.

In addition to the several parts named we provide a safety-catch 39, pivoted at 40 20 to the frame H and normally acted on by a spring 41, Fig. 4, tending to throw the lever to the position shown in that figure. The lower end of this lever 39 has a pin-and-slot connection with a link 42 on a crank 43, secured to the shaft 27. A screw 44 permits of 25 an adjustment of this pin-and-slot connection.

The operation of the described device is as follows: When the water in the collecting-chamber is at its lowest level, the parts will be 30 in the position shown in Fig. 1, with the ball-float down and the weighted end of the lever 28 tipped up and held by the catch-lever 36 in the position shown. The safety-catch lever 39 has also been drawn back at its lowest end by the crank 43 and out of engagement at its upper end with the lever 22, carrying the valve 20, so that the latter is then firmly held to its seat by the spring 24. As 35 the water accumulates in the collecting-chamber the float will rise, and its antifriction-roller 38 coming into contact with the catch-lever 36 will throw the latter out of engagement with the shoulder 37 of the counterweighted lever. The weighted end of the latter will then instantly fall to the position shown in Fig. 4 and through its shaft 27 will lift the spindle 26 and lever 22 against the action of the spring 24 and raise the valve 20 40 from its seat. At the same time the simultaneous movement of the crank 43 on the shaft 27 will free the lower end of the lever 39, so that the spring 41 will throw the upper end of the safety-catch lever 39 under the nose of the lever 22 to maintain the valve 20 45 in the open position until sufficient quantity of water has been allowed to flow from the collecting-chamber to warrant the closing of the valve again. As the float descends its 50 pin-and-slot connection with the lever 28 will elevate the weighted end of the latter and will lower its opposite end until the nose of the catch-lever 36 slips over the shoulder of the lever 28 and locks it in the position of 55 Fig. 1, as indicated in Fig. 3, and then imme-

diately thereafter the lever 39 will have been pulled out from under the nose of the lever 22. We so adjust the parts that the action will be that described—that is to say, that the counterweighted lever 28 will be locked 70 for a certainty before the valve 20 is allowed to close.

On the larger machines the main valve E, opening into the collecting-chamber D, is supplemented by a by-pass valve, as illustrated in Fig. 1^a, the purpose of which is to 75 permit the equalization of the steam-pressure in the baffle and collecting chambers, and thus ease the raising of the main valve E. Lateral openings a a in the neck of the valve E admit the steam from the baffle-chamber to the chamber X, and vertical openings b b in the valve-plate permit its passage into the collecting-chamber D upon the raising of the spindle e before the valve E 85 is raised from its seat. When the spindle e is depressed again, the head e will come to its seat and close the communication through the passages a a and b b.

In Fig. 6 we have shown a modification in 90 which the water-outlet valve instead of being operated by the steam-pressure is operated by direct mechanical connection from the lever 22. This is accomplished simply by pivoting to the lever 22 in place of the steam-valve a long stem 45, having at its lower end a valve 46, adapted to a seat 47 in a piece 49, screwed or otherwise attached to the casing. We may also make provision for operating 95 this water-valve by hand. For this purpose 100 we may secure to the stem 45 a collar 51, on the under side of which bears a bent lever 52, whose other arm is acted upon by a stem 53, passing through a stuffing-box in the casing, so that by inward movement of the stem actuated by a handle on the outside the valve 46 may be raised from its seat by hand, if desired. In this casing, Fig. 6, we have shown 105 a different form of inlet from the baffle-chamber from that illustrated in Fig. 1. In Fig. 6 110 we have shown it as adapted for a pipe connection, either to the baffle-chamber or to any other source of water-supply. Immediately under the water-inlet 54 is a distributing-plate 55, so that the full force of an inrush of 115 water may not come directly onto the float.

We claim as our invention—

1. The combination of a collecting-chamber having a water-discharge valve, with a weighted lever controlling said valve, a float 120 coöperating with said lever, a safety-catch to hold the valve open while the float is falling, a catch-lever to hold the weighted lever up until tripped by the float, and a connection from the weighted lever to the safety-catch 125 to operate the latter.

2. The combination of a collecting-chamber having a water-discharge valve with a spring-actuated means tending to close the valve, a weighted lever to open it, a float con- 130

trolling the lever, a safety-catch to hold the valve open while the float is falling and means to trip the safety-catch when the float has descended.

5 3. The combination of a collecting-chamber having a water-discharge valve with a weighted lever controlling said valve, a float coöperating with said lever, a safety-catch to hold the valve open while the float is descending and means for tripping it, and a catch-lever to hold the weighted lever up until tripped by the float.

10 4. The combination of a collecting-chamber having a water-discharge valve and a piston controlling said valve, with a valve controlling the supply of steam to the said piston, a spring and a weighted lever controlling said steam-valve, a float coöperating with the weighted lever, a safety-catch to hold the

steam-valve open while the float is falling and 20 means to trip the safety-catch when the float has descended.

5 5. A steam-eliminator having a baffle-chamber containing baffle-plates and below that a collecting-chamber with a valve between the two having a vertically-operating stem passing up between the baffle-plates and through a stuffing-box in the top of the casting.

In testimony whereof we have signed our 30 names to this specification in the presence of two subscribing witnesses.
